PAPER POSITIONING DEVICE FOR FEED
MECHANISMS OF PRINTING PRESSES
AND THE LIKE

William H. Shackleton, Wayzata, Minn.

Application February 21, 1934, Serial No. 712,338

3 Claims. (C.I. 271—53)

My invention relates to feeding machinery of the Cross type such as that used in connection with printing presses, folding machines and other paper handling apparatus and particularly relates to an equalizing device for automatically adjusting the position of a sheet of paper about to be delivered from a Cross feeding machine to another paper handling machine that the sheet will be started into said last mentioned machine in a definite predetermined relation to the moving parts of said last mentioned machine.

In Cross feeders considerable inconvenience and waste of paper stock is occasioned by failure of the Cross feeder to stop each sheet of paper in a definite position preparatory to delivery of the sheet to the machine served by the Cross feeder. Some sheets are stopped forward and some rearward of the desired position. Such inaccurate positioning of sheets results in sheets starting into the machine served in various positions relative to the moving parts of that machine. In multi-color printing, where a given sheet must undergo a separate printing operation for each color involved and Cross feeders are used to feed the sheets into the printing presses, it is obvious that such inaccurate operation will result in inaccurate registry of the various colors. Many sheets must be discarded because of such inaccurate registry with the result that production is reduced and much paper stock is wasted.

An object of my invention is to provide an efficient and accurate device for attachment to a Cross feeding machine to align the leading edge of a sheet of paper about to be delivered from the Cross feeder to another paper handling machine with a definite predetermined line whereby each sheet will be delivered to said last mentioned machine in identical relation to the moving parts of said last mentioned machine.

Another object is to provide such a device which may be readily attached to certain parts of a Cross feeder, which will obtain its actuating energy from certain moving parts of the Cross feeder and which will be actuated by said Cross feeder to perform its functions automatically.

Still another object is to provide such a device including means for pulling a sheet of paper from a position wherein its edge is adjacent a predetermined line to a position wherein its edge is at said line and means for preventing movement of the edge of said sheet to a position beyond said line.

A further object to provide such a device wherein all parts thereof are automatically removed from the path of a sheet of paper after po-

sitioning said sheet so as to permit unobstructed passage of said sheet from the Cross feeder to the paper handling machine served by the Cross feeder.

A still further object is to provide such a device of inexpensive, simple and rugged construction and capable of efficient, accurate and reliable performance of its function without damaging or marking paper sheets handled thereby.

These and other objects and advantages of the invention will be more fully set forth in the following description made in connection with the accompanying drawings, in which like reference characters refer to similar parts throughout the several views, and in which:

Fig. 1 is a general top view of certain parts of a Cross feeder with my equalizing device operatively attached thereto;

Fig. 2 is a vertical sectional view taken along the line 2—2 of Fig. 1, as indicated by the arrows, 20 including a side view of my equalizing device;

Fig. 3 is a side view of my equalizing device and certain parts of a Cross feeder, with which it is associated drawn to an enlarged scale and showing the device in one position in full lines and in 25 another position in dotted lines;

Fig. 4 is a vertical sectional view taken along the line 4—4 of Fig. 3 as indicated by the arrows;

Fig. 5 is a side view of my device with certain parts thereof in a partly operated position; 30

Fig. 6 is a horizontal sectional view taken along the line 6—6 of Fig. 3 as indicated by the arrows;

Fig. 7 is a side view of a portion of another and preferred form of my invention, and

Fig. 8 is a sectional view taken along the line 35 8—8 of Fig. 7.

A cross feeder is a machine which, as is well known, in the printing art, is used to feed sheets of paper stock to other paper handling machines, one sheet at a time. The paper handling machine served by a Cross feeder may be a printing press, a folding machine or some other form of paper handling machine. In any case the cross feeder and the machine served thereby are so arranged with respect to each other that sheets 40 of paper may run successively through the two machines as through a single machine and the two machines are geared together or driven by a common source of power so as to synchronize the motions of the parts of the respective machines. 45

In the portion of a Cross feeder with which my positioning device is used, sheets of paper are propelled, one at a time, down a sloping board 10, known as the lower board, by means of wheels 55

11, known as comber wheels. Fig. 1 shows a portion of the lower board 10 and one of the comber wheels 11. There are always two or more comber wheels on each Cross feeder aligned axially with each other and spaced apart transversely of the machine. The comber wheels 11 are power driven so as to rotate continuously and are mounted on a swingable member 12 so that they may be raised out of contact with the sheet of paper P therebelow. In connection with each comber wheel 11 there is a comber foot 13 which may be raised and lowered by operating the toggle 13a. Mechanism (not shown) is provided for lowering the foot 13 and raising the comber wheel 11 when a sheet of paper P controlled thereby has been propelled approximately to a predetermined position. The foot, in contact with the sheet of paper P, arrests motion of the sheet P through frictional engagement therewith. The mechanism for lowering the comber foot 13 and raising the comber wheel 11 is actuated by rockable cut-out shaft 18 on which is mounted cut-out fingers 18a which are raised by the leading edge of the sheet of paper P as the leading edge approaches said predetermined position. Cut-out top-guards 19, each having a forked lower end portion, are so positioned that the cut-out fingers 18a are respectively located between the side members of the forked lower end portions of the respective top guards 19. The cut-out fingers 18a and the cut-out top guards 19 are located in positions spaced laterally of the Cross feeder from the positions in which my devices are installed. In the approximate predetermined position, referred to above, the leading edge of the sheet of paper P overhangs the forward end of the lower board 10 and is disposed above the feed roll wheels 14 which are continuously rotating. Above the feed roll wheels 14, drop roll wheels 15 are supported on swingable arms 15a so that they may be lowered toward the feed roll wheels 14. The lowering of the drop roll wheels 15 is effected through mechanism (not shown) positively connected to and synchronized with the paper handling machines (such as a printing press or folding machine), to which the Cross feeder delivers sheets of paper. The timing of the drop roll wheel lowering mechanism is so arranged that the drop roll wheels 15 will be lowered each time that the moving parts of said paper handling machine are in a definite predetermined position. When the drop roll wheels 15 are lowered all the way they press the leading edge portion of the sheet of paper P against the continuously rotating feed roll wheels 14 which then propel the sheet into said paper handling machine. Since the operating mechanism for dropping the drop roll wheels 15 is synchronized with the mechanism of said paper handling machine it is apparent that successive sheets of paper would be fed into said paper handling machine in precisely the same relation to the moving parts of the paper handling machine if, and only if, the leading edge of each sheet is positioned along precisely the same line above the feed roll wheels 14 before the drop roll wheels 15 are lowered. However, in the Cross feeders now in use, such accurate positioning of sheets is not very closely approximated and the result is that sheets fed to the paper handling machine are not all started into that machine in the same relation to the moving parts of that machine. This brings about inaccurate results necessitating rejection and wastage of many sheets. One example is

found in multi-color printing wherein each sheet is passed through a printing press once for every color printed and wherein such inaccuracy will result in failure of the various colors to register on the sheet. The mechanical parts of a cross feeder referred to above are of conventional construction well known in the printing art and my positioning device is for use in cooperation with these parts to effect accurate positioning of a sheet of paper prior to lowering of the drop roll wheels 15 as will be described. 5

Referring to the drawings, the parts of my device are mounted on a stationary round spacer bar 16 and a continuously rotating shaft 17, both of which are conventional parts of a cross 15 feeder and extend transversely thereof. For purposes of the following description, the rear end of the Cross feeder will be considered to be the end at which paper stock enters the Cross feeder and, in accordance therewith, the rearmost parts 20 shown are those in the uppermost portion of Fig. 1 and in the right hand portions of Figs. 2, 3, and 5.

A bracket 20 extends rearwardly and slightly downwardly from the spacer rod 16 and is 25 mounted thereon by means of a portion of the bracket 20 forming a split clamping member 20a which encircles the rod 16 and is drawn into clamping relation therewith by means of screws 20b. The free end portion of the bracket 20, 30 situated rearwardly and downwardly from the clamping member 20a, is bifurcated to form a spaced pair of lugs 20c and the lugs are respectively horizontally apertured in horizontally aligned portions thereof. 35

A normally vertically disposed guage plate 21, having a pair of horizontally aligned and spaced, horizontally apertured lugs 21a formed on the medial portion of the rearwardly facing side thereof, is swingably mounted on the lugs 20c 40 of the bracket 20 by means of a pin 22 extending through all of the respective apertures in the lugs 20c and 21a. The gauge plate 21 is provided with a large opening 21e in its medial portion for projection therethrough of the 45 bracket 20. The lower portion of the plate 21 is provided with a notch 22 located centrally between the vertical edges of the plate and extending from the lower edge of the plate to a point a moderate distance thereabove as shown. The 50 notch 22 divides the lower end portion of the gauge plate 21 into two legs 21b, at the lower end of each of which is formed a rearwardly projecting and diverging pair of guide lips 21c, as best shown in Fig. 5. 55

An adjustable stop screw 23 is mounted in a portion of the bracket 20 so that the head of the screw 23 will serve as a stop engageable with the upper portion of the gauge plate 21 to limit forward movement of said upper portion and hence rearward movement of the lower portion of the gauge plate. A locknut 23a is provided on the screw 23 for use in locking the same in an adjusted position. 60

The upper end portion of the gauge plate 21 is 65 of reduced width and is provided with a forwardly projecting stud 21d having an aperture therein to which the rear end of a helical tension spring 24 is connected. An apertured lug 25 extends substantially upwardly from the uppermost portion of the clamping member 20a of the bracket 20. A spring anchoring adjustment screw 26 extends through the aperture in the lug 25 and carries an adjustment nut 26a bearing against the forward side of the lug 25. The rear or free end of the 70

screw 23 has a transverse aperture therethrough in which the forward end of the spring 24 is retained. The spring 24 obviously provides yieldable means for normally maintaining the upper portion of the gauge plate 21 in contact with the stop screw 23.

A depending positioning arm 27 is pivotally mounted at its upper end on the pin 22 between the lugs 20c of the bracket 20 so as to be movable with respect to the bracket 20 and with respect to the gauge plate 21. The lower end portion of the arm 27 extends forwardly in a portion 27a, then downwardly in a portion 27b and rearwardly in a portion 27c so as to form a rearwardly opening U-shaped structure comprising the portions 27a, 27b, and 27c. The lowermost portion 27c is cut away at the forwardmost part of its upper side to form a shallow notch 27d and, from this notch to the rear end of the portion 27c, the upper side of the portion 27c forms a gripping surface for cooperation with other parts as will be described.

A lever 28 extends through an aperture in the arm 27 located approximately at the junction of the portions 27a and 27b of the arm 27 and is pivotally mounted therein by means of a pin 28a which extends through the lever 28 and the arm 27. The lower portion of the lever is formed into a flat gripping finger 28b having a lower surface shaped to nest against the gripping surface of the portion 27c of the arm 27 immediately thereabove and in parallel relation thereto when said finger is in its lowermost position. The finger 28b and the upper side of the portion 27c of the arm 27 comprise a cooperating pair of gripping elements and the rearmost portions thereof are shaped to diverge rearwardly with respect to each other. The parts of my device described above are so located that, when the finger 28b is in closely spaced relation with the portion 27c of the arm 27, the space between the finger 28b and the portion 27c is aligned with the space between the guide lips 21c and also is aligned with the upper surface of the lower board 10. The upper arm 28c of the lever 28, extends upwardly from the pin 28a and at its upper end is engageable with the forward or free end of a stop 29 which is attached to and extends forwardly from the medial portion of the gauge plate 21. The lower end of a helical tension spring 30 is connected to the upper end portion of the lever arm 28c by means of an apertured lug 28d formed thereon. An adjustment screw 31 extends downwardly through a vertically apertured lug 27d formed on the forward side of the uppermost portion of the arm 27 and an adjustment nut 31a is mounted on the screw 31 above and bearing against the lug 27d. The upper end of the spring 30 is connected to the lower end of the screw 31 by means of a transverse aperture located in the lower end portion of the screw.

A horizontally apertured bifurcated lug 27e is formed on the rear side of the medial portion of the arm 27 and a small horizontally apertured lug 27f is formed on the rear side of the arm 27 just above the portion 27a thereof.

A substantially sector-shaped cam 32, having a hub extending from both sides thereof to respectively provide projecting portions 32a and 32b, is rigidly mounted on the continuously rotating shaft 17 previously mentioned. The cam 32 and the projecting portions 32a and 32b are split to divide the same into symmetrical halves in order to facilitate mounting of the cam on the shaft 17. The projecting portion 32a is provided with clamping ears 32c equipped with clamping screws 32d for

the purpose of holding the two halves of the cam 32 together to rigidly grip the shaft 17. The remaining projecting portion 32b is provided with an annular groove 32e in the peripheral portion thereof.

A push-rod 33, for oscillating the positioning arm 27, carries at its rearward end a forked head or guide yoke 33a, the respective fork members 33b of which are confined in diametrically opposite portions of the annular groove 32e of the cam hub portion 32b so as to be forwardly and rearwardly slidable in the groove 32e. A screw-eye 34 is screw-threadedly mounted in the forward end of the push-rod 33. A lock-nut 34a is mounted on the screw-eye 34 to abut the forward end of the push-rod 33 to retain the screw-eye 34 in any desired adjusted position relative to the push rod 33. The forward or eye portion of the screw eye 34 is retained between the halves of the bifurcated lug 27e of the arm 27 by means of a pin 35 extending through the apertures of the lug 27e and the eye of the screw-eye 34. A downwardly extending apertured lug 33c extends from the lower edge of the forked head 33a adjacent the junction thereof with the pushrod 33. A helical tension spring 36 is connected at its respective ends to the lug 33c and the lug 27f of the positioning arm 27.

On the forked head 33a adjacent the point of junction thereof with the push rod 33, a roller 37 is revolvably mounted by means of a pin 37a in 30 position to engage the periphery of the cam 32.

In each Cross feeder equipped with my positioning devices at least two of my devices, spaced laterally of the Cross feeder, are installed so that they may act upon a sheet of paper cooperatively 35 and in unison.

Operation

As a sheet of paper P is propelled down the lower board 10 by the comber wheels 11, the leading edge of the sheet will strike and operate the cut-out finger 18a just prior to the sheet reaching the position thereof shown in Fig. 3. Operation of the cut-out finger 18a will then cause the comber foot and comber wheel operating mechanism to lower the comber feet 13 and raise the comber wheels 11 to frictionally engage the sheet of paper P to arrest movement of the sheet when the leading edge has reached a position approximating the position thereof shown in Fig. 3. Due to inaccuracy of the mechanism the leading edge of the sheet may stop in a position somewhat forward or rearward of that shown. It is to be noted that, in this position, the leading edge portion of the sheet is disposed between the gripping finger 28b and the gripping surface of the portion 27c of the positioning arm 27 of my device.

Immediately following the above described operation, the continuously rotating cam 32, the periphery of which is engaged with the roller 37, reaches positions wherein it slowly forces the roller 37 and parts on which the roller is mounted forwardly against the tension of the spring 36, thereby moving the positioning arm 27 forwardly. As the positioning arm 27 moves forwardly it carries the pivot pin 28a, on which the lever 28 is mounted, forwardly with respect to the stop pin 29 mounted on the gauge plate 21. The spring 30 keeps the upper end of the lever 28 in contact with the stop pin 29, resulting in clockwise rotation of the lever 28 relative to the positioning arm 27 as viewed in Fig. 5, until the gripping finger 28b has engaged the sheet of paper P and further relative rotation of the lever 28 is prevented by such engagement. Further forward move- 75

ment of the positioning arm 27 causes the upper end 28c of the lever 28 to leave contact with the stop 29, thus allowing the spring 30 to pull the upper end 28c of the lever 28 toward the rear to 5 cause the gripping finger 28b to exert downward pressure and hence tightly grip the sheet of paper P. When the sheet of paper P has been firmly gripped between the gripping finger 28b and the portion 27c of the positioning arm 27, it will be 10 drawn forwardly with the arm 27, guided by the guide lips 21c, until the leading edge of the sheet engages the portions of the gauge plate 21 lying, respectively, between the bases of the guide lips 21c of each pair thereof. When such engagement 15 has taken place slippage of the gripping elements 28b and 27c with respect to the sheet of paper P will take place during further forward movement of the positioning arm 27, thus permitting the sheet of paper to remain stationary with its 20 forward edge in contact with the gauge plate 21. Just prior to engagement of the forward side of the positioning arm 27 with the rearward side of the gauge plate 21, the point on the gripping elements 28b and 27c at which divergence thereof 25 begins has passed the leading edge of the sheet of paper P and all contact between the gripping elements and the sheet has ceased. The sheet will then remain stationary until it is propelled forward by other mechanism as will be described. 30 After engagement between the arm 27 and the gauge plate 21 has taken place, the gauge plate is carried forwardly against the tension of the spring 24 by the arm 27 until the position shown in dotted lines in Fig. 3 has been reached. In 35 this position, it will be noticed, the positioning arm 27, the gauge plate 21 and all parts associated therewith are out of line with the sheet of paper P so as to offer no obstruction to further forward movement of the sheet. All of the 40 operation so far described has taken place during movement of the cam 32 from a position wherein the roller 37 makes contact with the portion of the cam having minimum radius to a position where the roller has just reached the portion of 45 the cam having maximum radius. Rotation of the cam may be continued through a considerable angle without effecting any movement of the parts operated thereby since the portion of the cam having maximum radius extends through a 50 considerable angle as may be seen in Fig. 3.

The leading edge of the sheet of paper P is now disposed along a definite line accurately predetermined by the initial or normal position of the gauge plate 21 and the leading edge portion is disposed above the continuously rotating feed roll wheels 14. When the drop roll wheels 15 are lowered they press the sheet of paper P into frictional engagement with the feed roll wheels 14 which then propel the sheet into the machine served by the Cross feeder. Since the mechanism for lowering the drop roll wheels is synchronized with the machine served by the Cross feeder and the leading edge of the sheet is located along a definite predetermined line before lowering of the drop roll wheels occurs, it is apparent that the sheet will be delivered into the machine served in a definite relation with the moving parts of the machine served. Also, if the operation described 60 above is repeated for delivering other sheets, it is obvious that all of the sheets delivered will pass through the machine served in the same identical relation to the moving parts thereof. Further, if a given sheet is delivered to the machine several 65 times, this sheet will pass through the machine in

the same relation to the moving parts thereof each time.

After a sheet has been propelled by the feed roll wheels to a point beyond the arm 27 and the gauge plate 21, the cam 32 has rotated to a position wherein the roller 37 has passed the end of the portion of the cam having maximum radius. The roller 37 and the parts to which it is attached are then returned to their initial positions by force exerted by tension in the springs 36 and 10 24 and force transmitted to the upper end 28c of the lever 28 by the stop 29. The mechanism is then ready for repetition of the cycle of operation described above so as to position another sheet 15 of paper. In practice the described cycle is, of course, continuously repeated for considerable periods of time.

As has been mentioned, two or more of my positioning devices are used in one Cross feeder and are aligned transversely of the Cross feeder. 20 Accordingly, it is apparent that with devices for pulling two or more points on the leading edge of a sheet to predetermined positions the leading edge is not only pulled up to a given position, longitudinally of the Cross feeder, but is also accurately aligned transversely of the Cross feeder. 25

It will be noticed that various adjustment means are provided in my positioning device whereby the device may be adjusted for smooth and accurate operation. The adjustment screw 30 33 is adapted for use in setting the gauge plate 21 to predetermine the position in which the device will place the leading edge of a sheet of paper. The adjustment nut 26a is for adjusting the tension on the spring 24. The adjustment nut 35 31a is for adjustment of the tension in the spring 30 and consequently affects the strength with which the gripping elements 28b and 27c will grip a sheet of paper. The screw 34 may be used to alter the relation between the respective normal 40 positions of the arm 27 and the gauge plate 21. Loosening the screws 26b will release the clamp 26a to permit adjustment of the bracket 28 on the spacer rod 16. Loosening of the screws 32d releases the cam 32 so that the same may be rotated on the shaft 17 to properly synchronize the 45 action of my positioning device with the actions of the various moving parts of the Cross feeder. 50

In the preferred form of my invention partly shown in Figs. 7 and 8, all parts not shown in 55 Figs. 7 and 8 are identical with the corresponding parts of the form of my invention described above and illustrated in Figs. 1 to 6 inclusive and are connected together in the same manner.

A push-rod 133 having a forked head or guide 55 yoke 133a with fork members 133b, all of which are identical with the corresponding parts 33, 32a and 32b of the previously described mechanism, is mounted on a screw-eye 134 and locked in position thereon by a locknut 134b. The screw-eye 60 134 is identical with the previously described screw-eye 34 and is similarly connected to the other parts of the mechanism.

A roller 137 is revolvably mounted on the yoke 133a by means of a pivot pin 137a. 65

The cam 132 is diametrically split and is mounted on the shaft 17 in the same manner as the cam 32 of the previously described form of the invention. A portion 132a extending to one side of the cam 32 carries clamping ears 132c equipped with clamping screws 132d by means of which the cam 132 is fixed to the shaft 17. 70

A portion 132b projecting from the remaining side of the cam 132, is provided with an annular groove 132e in which portions of the respective 75

fork members 133b of the guide yoke 133a are slidably retained.

The cam 132 is in the form of a relatively thick disk having a deep generally arcuate open-ended groove 132f formed in one face thereof as shown. The groove 132f which is of a width only slightly greater than the diameter of the roller 137, divides the face of the cam 132 into two ungrooved portions 132g and 132h of which the portion 132g 10 is shaped the same as the cam 32 of the first described form of the invention.

No spring corresponding to the spring 36 of the first described form is used and hence the apertured lugs to which such a spring would be anchored are omitted.

The operation of the last described form of my invention is identical to that of the first form with exceptions to be described. The roller 137 20 portions of the cam 132 defining the groove 132f in all positions of the cam 132 except those positions wherein the roller 137 is bearing against the circular outer periphery of the cam.

As the cam 132 moves the push-rod 133 forwardly, this movement is not opposed by spring pressure until the positioning arm 27 has made contact with the gauge plate 21. The remainder of the forward movement is then carried on against the tension of the spring 24.

As rotation of the cam proceeds while the positioning arm 27 and the gauge plate 21 are in their forwardmost position, the spring 24 exerts a pressure through the gauge plate and the positioning arm to hold the same in contact with each other and to hold the roller 137 in contact with the circular outer periphery of the cam 132. When the cam 132 has been advanced to a position wherein the roller 137 encounters the open end of the groove 132f the pressure exerted by the spring 24 acts to urge the roller 137 into the groove 132f 40 and to move the gauge plate 21 and the positioning arm 27 rearwardly. This action will continue only until the gauge plate 21 has returned to its normal position wherein its upper portion abuts the stop screw 23, at which time the roller 137 is within the groove 132f of the cam. Continued movement of the cam will result in rearward camming of the roller 137 and rearward movement of the push rod 133 and the positioning arm 27 entirely free of all spring action until the upper end 28c of the lever 28 makes contact with the stop pin 29. As rotation of the cam is further continued to complete the rearward movement of the roller 137, the push-rod 133 and the positioning arm 27, such movement will be resisted by the spring 38.

If either the positioning arm 27 or the gauge plate 21 should become obstructed when in their forwardmost positions so as to prevent rearward movement thereof, the roller 137 will not enter the groove 132f as the cam is rotated but instead will engage the circular outer periphery of the cam disk adjacent the portion 132h of the face of the cam disk. It follows that force will not be applied to move the obstructed parts rearwardly and hence that the risk of breakage or distortion of the obstructed parts or other parts associated therewith will not be incurred.

It is apparent that I have invented a novel, simple, accurate and inexpensive device for positioning sheets of paper in a Cross feeder.

It is also apparent that my device is readily adaptable for use in many other types of machinery for handling various kinds of sheet material.

It will, of course, be understood that various changes may be made in the form, details, proportions and arrangement of the parts, without departing from the scope of my invention, which, generally stated, consists in a device capable of carrying out the objects above set forth, in the novel parts and combinations of parts disclosed and defined in the appended claims.

What is claimed is:

1. Mechanism for accurately positioning sheet material for action thereupon by a machine, having in combination, a sheet support, a gauge plate disposed adjacent said support, a positioning member movable with respect to said plate, gripping means mounted on said member for gripping the leading edge of a sheet of material, a pair of guide members mounted on said plate and extending divergently toward said sheet and means for oscillating said member so that the same, when moving in one direction, will pull a sheet gripped by said gripping means into abutment with said gauge plate, said gripping means being constructed and arranged to slip with respect to said leading edge of said sheet when said abutment has taken place whereby said sheet will be positioned with its leading edge aligned with said gauge plate.

2. Mechanism for accurately positioning sheet material for action thereupon by a machine, having in combination, a sheet support, a swingable gauge plate located adjacent said support, stop means for limiting movement of said plate in one direction, yieldable means for normally holding said plate in engagement with said stop means, a positioning arm swingably mounted with respect to said plate, means for gripping the leading edge of a sheet disposed on said support, said gripping means being carried by said arm, and means for swinging said arm whereby the same, in the first portion of its movement, will draw the leading edge of said sheet into abutment with said gauge plate, said gripping means being constructed to slip with respect to said sheet when further movement takes place after said abutment has been effected and to completely leave contact with said sheet shortly thereafter, said positioning arm being so arranged with respect to said gauge plate that it will abut said plate after said gripping elements have left contact with said sheet and will swing said plate with itself during the last portion of the movement of said arm whereby both said arm and said plate will be disposed entirely out of alignment with said sheet.

3. In combination with a sheet material feeding mechanism which includes a sheet support and means for placing a sheet on said support with the leading edge of said sheet overhanging the forward edge of said support in approximate position for said sheet to be acted upon by a machine, a mechanism for accurately positioning said sheet comprising, a swingable gauge plate mounted slightly forward of the leading edge of an approximately positioned sheet and having a portion aligned with said sheet, stop means for limiting rearward movement of said plate, yieldable means for normally holding said plate against said stop means, a positioning arm swingably mounted with respect to said plate, releasable gripping means mounted on said arm for gripping the leading edge of said sheet, means for oscillating said arm, means actuated through movement of said arm for maintaining said gripping means in non-gripping position when said arm is at or near its rearward limit of movement, yieldable means for

urging said gripping means into gripping position whereby the overhanging portion of said sheet will be gripped by said gripping means during the first portion of forward movement of said arm 5 and will be drawn into a position wherein the leading edge of said sheet abuts said plate, said gripping means being arranged and constructed to slip with respect to said sheet when said abutment has been effected and to completely leave 10 contact therewith shortly thereafter, and a lost

motion connection between said arm and said plate for transmitting motion from said arm to said plate during the latter portion of the forward movement of said arm following disengagement of said gripping means from said sheet whereby both said arm and said plate will be disposed out of alignment with said sheet when said arm is at or near its forward limit of movement. 5
